UNITED STATES PATENT OFFICE.

LESTER A. WERNERY, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,172,853.

Specification of Letters Patent. Patented Feb. 22, 1916.

Application filed May 7, 1914. Serial No. 837,078.

To all whom it may concern:

Be it known that I, LESTER A. WERNERY, a citizen of the United States, residing in Brooklyn borough, in the county of Kings, 5 city and State of New York, have invented certain new and useful Improvements in Type-Writing Machines, of which the following is a specification.

This invention relates to typewriting machines, and particularly to means whereby labels and other small work-pieces, incapable of being fed over the platen by the usual means, may be held to the platen while typewriting is performed thereon, and may be 10 advanced in line-spacing movement with the platen irrespective of the usual guiding devices.

A curved plate conforms to the contour of the platen and lies snugly thereon, and 15 has a rearward shank to enter a slot in the platen surface. At a point within the body of the platen said shank engages an eccentric or shaft, which in its rotating action causes said shank to slide in and out through 20 said slot and thereby to move the plate to and from the platen surface; thus alternately presenting a space between the plate and platen, to receive a label or other small work-piece, and clamping upon said label or 25 work-piece to grip it firmly to the platen. This work-piece holding plate may conveniently be arranged toward the left end of 30 the platen where the platen surface is commonly used for printing and usually more 35 serviceable in supporting the marginal portions of work-sheets. Moreover the plate may be so thin and lie so snugly against the platen surface, being recessed therein if desirable to have it flush with the platen surface, 40 that on occasion writing may be performed on sheets overlying said plate.

The use of the plate is facilitated by an adjustable stop device mounted on the carriage, which engages an end of said eccentric shaft protruding through the platen end and held to a stop by a spring on the platen, and whereby in the rotation of the platen said shaft is rocked to separate the plate from the platen surface, and the platen is 45 arrested under the increasing tension of the spring at that point where said plate has been moved away from the platen surface to receive the work-piece; whereupon the lower edge of the work-piece is inserted be-

tween the upper portion of said plate and 55 the platen surface, and then the platen is turned backwardly to remove the spring-pressed end of the eccentric shaft from the influence of the stop device, and thus allow 60 said spring to rock said shaft backwardly and return the plate to the platen surface. The work-piece which is in this manner clamped to the platen is in position thereon 65 to receive lines of writing, being further held to the platen, if desirable, by an auxiliary finger carrying a roller, mounted on the carriage to be swung into and out of operative position. Upon completion of the 70 lines of writing, further rotation of the platen again brings into operation the plate-releasing mechanism to permit the removal of the written on work-piece and the insertion of another work-piece. In this manner successive work-pieces may be applied to 75 and removed from the platen with a minimum of manual labor, on account of the automatic operation of the clamping and releasing means which perform their duties during the forward and return movements of the platen.

80 Other features and advantages of my invention will hereinafter appear.

In the accompanying drawings, Figure 1 is a perspective end elevation of portions of a platen and carriage with my improvements applied thereto, the platen being broken-away to disclose the operating mechanism as projected to enable the work-piece holder to receive or reject a work-piece. Fig. 2 is a similar view showing the work-piece 85 holder in operative position. Fig. 3 is an end elevation showing the stop device adjusted to operative position. Fig. 4 is a similar view showing the plate separated from the platen surface through the operation of its actuating mechanism with the stop device. Fig. 5 is a similar view showing the stop device adjusted to inoperative 90 position. Fig. 6 is a transverse section through the platen to show the slot and plate mechanism therein. Fig. 7 is a perspective rear elevation of the locking plate and its actuating parts. Fig. 8 is a vertical, longitudinal section of a portion of the platen, also showing the stop device and its 95 operative conjunction with the plate mechanism.

100 While applicable to typewriting machines

of various characters, my invention is here shown as applied to an Underwood machine, wherein the platen 1 is shown as supported by frame 2 mounted on carriage 3. The 5 line-space wheel 4 and usual button 5 for independently rotating the platen are also shown, though it has not been thought necessary to show the operating mechanism for the line-space wheel. Though not a part 10 of these improvements, I have also indicated at 6 the feed rolls and at 7 the guide fingers whereby work-sheets of ordinary sizes are advanced over and held to the platen surface, because my improvements 15 may, under certain conditions, be considered auxiliary to these devices.

In carrying my invention into effect, I provide a longitudinal slot, as at 8, through the platen surface, into the hollow interior 20 of said platen, said slot being adapted for the reception of the shank 9 which carries the curved clamping plate 10 that is adapted to lie snugly upon the surface of the platen when said shank 9 is drawn within 25 said slot. By having the slot for the shank extended longitudinally, and arranged near the middle of a plate as shown, and by having a plate concentric with the platen, I am enabled to have a sure movement of the 30 plate toward the platen, and a quick and even grip upon a card. Said shank 9 has an extension 11 provided on one face with a transverse recess 12 to receive an eccentric portion 13 of a rod or shaft 14 that is journaled at one end in a stud 15 secured within the platen and forming a bearing, and at its other end said rod or shaft 14 is passed through an orifice 16 therefor in the platen end to serve as a bearing. The shaft 40 end which protrudes through the platen end carries a bearing plate 17, which extends forwardly to include in its upward path, when rotated with the platen, the nose 18 of an adjustable stop 19, said plate being 45 held in that extended position by a stop pin 20 against the upward urging thereof by a spring 21, which may be coiled around the platen hub 22 and secured to the platen end, as seen.

50 It will be understood that the forwardly extending position of the plate 17 referred to, is that indicated in the drawings, and is relative to the position of the platen for employment of the plate 10.

55 The recess 12 in the shank extension 11 is covered by a leaf spring 23, of greater length than said extension, and adapted, when the shank is introduced within the slot 8, to spring apart from said extension 60 and allow the eccentric or crank portion 13 of the shaft to enter said recess 12.

The adjustable stop 19 for actuating plate 10 through the instrumentalities described, is suitably mounted upon the carriage, and 65 as shown may consist of a strip depending

from the usual cover plate 24 for the line-space mechanism, said strip terminating at its lower end in the off-set portion or nose 18, and at its upper end being bent at right angles to form the horizontal portion 25 70 with slot 26, through which slot a threaded member 27 may enter the forward screw hole in the platen frame, whereby the cover plate is secured in place, said member 27 thus also serving to adjustably secure said 75 stop 19 upon the carriage. Obviously, by loosening the member 27, the stop 19 may be shifted to and fro through the extent of its slot, thereby effecting the adjustments, respectively, whereby said stop may be held 80 either in or outside the path of movement of the plate 17.

Figs. 1 to 4 inclusive, show the stop 19 as operatively adjusted, and Fig. 5 shows said stop as shifted forwardly to be out of the 85 path of the operating mechanism for plate 10, so that in this latter position of the stop the platen may be rotated for line spacing without affecting said plate.

With the stop 19 adjusted as in Fig. 2, 90 wherein a work-piece 28 is seen to be held in position by plate 10, the platen is free to advance in line-spacing a further degree before said work-piece is released. In Fig. 1 that further advance has been made, the 95 plate 17 has met the stop 19 in the rotation of the platen, and having yielded against its spring support because restrained by stop 19 while the platen has advanced, it has by that act rocked the shaft 100 14 and caused the crank 13 to slide the shank outwardly, thereby separating the plate 10 from the platen surface. Thus the work-piece 10 shown in Fig. 1 may represent either a work-piece ready for removal 105 or a new one just inserted. The following retrograde action of the platen again clamps the plate 10 to the platen surface allowing it to grip the new work-piece while the platen is returning to bring said work-piece into printing position.

In order to hold the upper portion of the work-piece against the platen while being printed upon by the types, as 29, I may provide a guide finger 30, pivoted at 31 to 115 the front rail of the carriage, to swing horizontally into and out of operative position, said finger 30 having a roller 32 adapted, when said finger is extended, to lie against the work-piece to hold it against the 120 platen.

It should be noted that the upper edge of the plate 10 lies below the printing point on the platen at that time when the platen releasing mechanism is about to become operative, and that the plate release for removal of the printed work-piece and insertion of a new work-piece occurs under the arrangement disclosed immediately after the completion of writing upon a work-piece. 130

It is intended to demonstrate by the foregoing account that the extent of the reciprocable movement required to be imparted to the platen, either in turning it by hand in both directions, or in advancing by the line space lever and returning by hand, is no more than is necessary to feed forwardly the label or other small work-piece for which my invention is designed, and that in 5 that limited movement the mechanical operations are performed for release and resetting of the work-piece holding plate.

Variations may be resorted to within the scope of my invention, and portions of the 10 improvements may be used without others.

Having thus described my invention, I claim:

1. In a typewriting machine, in combination, a rotatable platen having a slot lengthwise thereof, a work-piece clamp adapted to engage the surface of said platen, a shank on said work-piece adapted in thickness to the width of said slot, and extending practically the length of said clamp, an extension 20 on said shank, a rod rotatable within the platen and having an eccentric portion engaging said extension, a spring, an extension on said rod adapted to be engaged by said spring to cause the rod to hold the 25 work-clamp against the surface of the platen, and a stop fixed in the path of said extension so as to release the work-clamp when the platen has been rotated to a certain point.
2. In a typewriting machine, in combination, a rotatable platen with a longitudinal slot in the surface thereof, a work-piece clamp adapted to engage the surface of said platen on both sides the slot, a slot engaging 30 shank on the clamp, an extension to said shank, a hole in said extension, a latch over said hole, a rotatable rod within said platen, an eccentric portion on said rod, said rod being so mounted that the said eccentric 35 portion may engage the hole in said shank extension and be latched therein, an extension on said shaft, a spring coiled about the platen shaft and engaging said shaft extension to draw the work-clamp against the 40 platen, and means engaging said shaft extension whereby the work may be released from said work-clamp at a predetermined point in the rotation of the platen.

3. In a typewriting machine, the combination with a revoluble platen, of a plate movable to and from the platen surface to engage and release a work-piece, a shank on said plate, a spring engaging said shank, a fixed stop adjustable to and from its operative 45 position, and means upon said plate operable by said stop whereby said plate is released in the rotation of said platen.

4. In a typewriting machine, the combination with a revoluble platen, of a plate movable to and from the platen surface to

engage and release a work-piece, a stop, a shank on said plate adapted to be entered through a slot in the platen surface, an extension on said shank having a recess on one face thereof and a spring to cover said 70 recess, and an eccentric rod adapted to engage with said recess and be held therein by said spring, said rod having an extension beyond the platen end where it meets said stop in the advance of the platen to 75 release said plate.

5. In a typewriting machine, the combination with a revoluble platen, of a plate movable to and from the platen surface to engage and release a work-piece, a stop, a shank 80 on said plate adapted to be entered through a slot in the platen surface, an extension on said shank having a recess on one face thereof and a spring to cover said recess, an eccentric rod adapted to engage 85 with said recess and be held therein by said spring, said rod having an extension beyond the platen end where it meets said stop in the advance of the platen to release said plate, and a spring to return said rod and 90 plate, to reseat the latter, on the return rotation of the platen.

6. In a typewriting machine, a platen having a longitudinally extending slot therein near one end, a shank fitting in said 95 slot, a plate concentric with the platen and extending both sides of the slot, secured to the shank, a spring tending to pull said plate against the platen, a bearing plate connected with the spring and plate, and 100 an adjustable stop with which said bearing plate may engage when the platen is fed forward to release the shank carried plate against the tension of the spring.

7. In a typewriting machine, in combination, a revoluble platen having a longitudinally extending slot near one end, a plate curved to fit the platen, a shank secured to the plate near the middle of its concave side, said shank fitting the slot, an inwardly extending extension 11 on said shank, a spring in the inner end of said extension, and a rod journaled in the interior of the platen having a crank or eccentric portion passing through 110 said extension opening, a spring acting on 115 said rod to hold said plate against the platen, and means on the carriage to release the plate against the tension of the spring.

8. In a typewriting machine, in combination, a revoluble platen having a longitudinally extending slot near one end, a plate curved to fit the platen, a shank secured to the plate near the middle of its concave side, said shank fitting the slot, an inwardly extending extension 11 on said shank, a spring 120 in the inner end of said extension, and a rod journaled in the interior of the platen having a crank or eccentric portion passing through said extension opening, a spring coiled about the platen axle, having one end 125

engaging the platen and the other engaging said rod so as to cause the eccentric part thereof to pull the plate against the platen.

9. In a typewriting machine having a carriage and a revoluble slotted platen, the combination of a plate movable to and from the platen surface to engage and release a work-piece, said plate being provided with an extended shank to fit said slot, a stop 10 having a slot by which it is adjustably mounted on said carriage, to be movable

into and out of operative position, and means arranged substantially centerwise upon said plate and fitting the slot in the platen operable by said stop whereby said plate is released in the rotation of said platen. 15

LESTER A. WERNERY.
